METER OR SIMILAR INSTRUMENT

Louis W. Pignolet, Chatham, N.J., assignor to Weston Instruments, Inc., Newark, N.J., a corporation of Delaware

Filed Dec. 4, 1967, Ser. No. 9,632

Term of patent 14 years

(Cl. D26—1)

FIG.1

FIG.2

FIG.3

FIG.4

FIGURE 1 is a perspective view of the meter or similar instrument showing my new design;

FIGURE 2 is a front view of the meter;

FIGURE 3 is a right end view of the meter; and
FIGURE 4 is a plan view of the meter.

The undisclosed end of the instrument is a mirror image of the end shown in FIGURE 3, and the rear is flat and plain in appearance except for the two brackets shown in FIGURES 3 and 4.

The dominant features of the design reside in the full line portions thereof.

I claim:

The ornamental design for a meter or similar instrument, substantially as shown and described.
